WRINGER MOP

Albert M. Jouban, Lafayette, La.

Application December 7, 1951, Serial No. 260,399

3 Claims. (Cl. 15—120)

1

This invention relates to floor mops, and more particularly to a floor mop having a mop-spreading pad and mop-wringing mechanism incorporated therein.

It is among the objects of the invention to provide an improved floor mop assembly including a handle, a mop secured to one end of the handle and mechanism connected between the mop and the handle for wringing the mop without removing the mop from the handle and without the necessity of any separate wringing device; which includes a pad or applicator of resilient material within the mop for spreading the mop over a floor area and resiliently pressing the mop against a floor surface but which pad does not interfere with the wringing of the mop; which provides both a stretching and a twisting or wrapping action on the mop strands in the wringing operation of the mop; and which is simple and durable in construction, economical to manufacture, and positive and effective in operation.

Other objects and advantages will become apparent from a consideration of the following description and the appended claims, in conjunction with the accompanying drawings, wherein:

Figure 1 is a side elevational view of a mop illustrative of the invention;

Figure 2 is a longitudinal cross-sectional view on the line 2—2 of Figure 1;

Figure 3 is a transverse cross-sectional view on the line 3—3 of Figure 1;

Figure 4 is a perspective view of the mop in mop-wringing condition;

Figure 5 is a side elevational view of the mop in the condition illustrated in Figure 4 with portions broken away and shown in cross-section to better illustrate the construction thereof;

Figure 6 is a side elevational view of a somewhat modified form of mop;

Figure 7 is a view similar to Figure 6, but with portions broken away and shown in cross-section to better illustrate the construction of the mop;

Figure 8 is a longitudinal cross-sectional view on the line 8—8 of Figure 6; and

Figure 9 is a longitudinal cross-sectional view on an enlarged scale showing the mop in mop-wringing condition.

With continued reference to the drawings, and particularly to the form of the invention shown in Figures 1 to 5, inclusive, the mop comprises a pad 10 of resilient material, such as vulcanized rubber, including a central boss 11 of generally cylindrical shape, open at one end and closed at the other end by a flat end wall 12, and an annular web or flange 13 secured to the boss 11

2

at the open end of the latter in surrounding relationship thereto and projecting outwardly from the boss. This web 13 is tapered in thickness from the boss to its outer, substantially circular edge, and is cup-shaped so that an outer annular portion 14 thereof substantially contacts a plane which contacts the outer side of the end wall 12 of the boss.

The boss 12 is internally screw-threaded, and an elongated handle 15 formed of wood or other suitable material has at one end a screw-thread formation 16 threaded into the boss 11 of the pad 10, so that the handle extends from the boss and is disposed substantially perpendicularly to the pad.

A tubular body 18 in the form of an elongated collar has a bore extending longitudinally therethrough and receiving the handle 15, and this collar is disposed on the handle adjacent the pad 10 and provided in its end remote from the pad with a screw-threaded counterbore 19. At its other end the collar 18 is provided with an external annular groove 20, and a tubular nut 21 is mounted on the handle at the side of the collar 18 remote from the pad 10.

The nut 21 has a bore extending longitudinally therethrough and receiving the handle 15, and has an externally screw-threaded portion 22 of substantially cylindrical shape adjacent the collar 18, and an annular flange 23 on its end remote from the collar, the flange 23 providing at its side adjacent the screw-threaded portion 22 an annular shoulder 24 which functions as a limit stop for the collar 18. The nut is provided with tapped holes extending radially of the flange 23 thereof, and a set screw 25 is threaded through one of these holes and bears against the handle 15 to lock the nut in adjusted position on the handle, and a hand lever 26 is threaded at one end into the other tapped hole in the nut flange and projects radially from the nut for a purpose to be presently described.

A group of mop strands 27 extend across the bottom wall 12 of the pad boss 11 and are bound, substantially at their mid-length location, to the boss 11 by a band 28 which extends around the mop strands and around an annular recess in the boss between the end wall 12 of the boss and the web 13 extending from the open end of the latter.

At their ends the mop strands 27 are bound to the collar 18 by a band 28 which extends around the end portions of the mop strands and forces these end portions into the annular groove 20 in the collar. The mop strands are angularly

arranged relative to each other, so that they completely surround the boss 11 and the adjacent end portion of the handle 15 and are doubled between the boss and the collar 18 and secured in doubled or folded-over condition by one or more circular rows of stitching, as indicated at 30, surrounding and spaced from the outer edge of the flange portion 13 of the pad 10.

The collar 18 is provided with a tapped hole intermediate its length, and a hand lever 31 is threaded at one end into the tapped hole in the collar and extends radially therefrom.

When the mop is used in its operative condition, as illustrated in Figures 1 and 2, the disc-shaped pad 10 holds the mop strands outwardly of the boss 11 and adjacent end of the handle 15, and resiliently presses the mop strands against a floor surface on which the mop is being used.

When it is desired to wring the mop, the hand lever 26 is grasped in one hand and the hand lever 31 in the other. The hand lever 31 is then moved along the handle 15 toward the hand lever 26 until the end of the nut 21 adjacent the collar 18 is entered into the outer end of the screw-threaded counterbore 19 in the collar. The hand lever 31 is then turned about the handle 15, while the hand lever 26 is used to hold the handle against rotation until the collar 18 has been fully threaded onto the nut 21. This threading of the collar 18 onto the nut 21 simultaneously stretches the mop strands 27 and twists or wraps the mop strands about the handle, and the flange portion 13 of the pad 10, which is folded during the movement of the collar toward the nut to the cup-shaped form illustrated in Figure 5. This simultaneous stretching and wrapping of the mop strands compresses the strands sufficiently to squeeze substantially all of the water from the mop. The screw-thread formation on the handle is in the same direction as the screw-thread formation 22 on the nut, so that the handle will not be unscrewed from the boss 11 while the collar 18 is being threaded onto the screw-threaded portion 22 of the nut 21.

In the form of the invention illustrated in Figures 7 to 9, inclusive, a plug 35 of elongated, cylindrical shape has at one end a screw-thread formation 36 threaded into the boss 11 of the pad 10, which is the same as the pad illustrated in Figures 1 to 5, inclusive, and previously described.

An elongated, tubular, inner member 37 telescopically receives the plug 35 in one end thereof and is secured at one end to the plug adjacent the boss 11, as indicated at 38.

The member 37 is provided with a spiral slot 40 which extends once therearound and from a location adjacent the end of the member remote from the plug 35 to a location intermediate the length of the member, and is also provided with a straight slot 41 which extends longitudinally thereof from a location adjacent the inner end of the spiral slot 40 to a location spaced from the end of the plug 35 remote from the boss 11 of the pad 10. The spiral slot 40 and the straight slot 41 are disposed in end-to-end relationship and extend along the member 37 for substantially equal distances, and the slot 41 is provided at its end adjacent the slot 40 with a lateral offset 42 to provide a bayonet joint connection to be later described.

The handle 15 is slidably received in the tubular member 37 and projects from the end of this tubular member remote from the pad 10. It has its inner end spaced from the adjacent end of 75 ceives the plug 35.

the plug 35 and carries adjacent its inner end a pin 43 which extends through the straight slot 41 in the tubular member 37.

A compression spring 44 is disposed in the tubular member 37 between the adjacent ends of the plug 35 and the handle 15.

An outer tubular member 45, somewhat shorter than the inner tubular member 37, receives and is slidably mounted on the inner tubular member. This outer tubular member has a spiral slot 46 which extends twice therearound and substantially from one end thereof to the other, having a total length substantially equal to twice the length of the spiral slot 40 in the member 37 or to the combined length of the spiral slot 40 and the straight slot 41 in the inner tubular member 37.

At its end adjacent the plug 35 the outer tubular member 45 is externally screw-threaded, as indicated at 47, and a nut 48 having an external annular groove therein is threaded onto the screw-threaded portion 47 of the outer tubular member 45.

The mop strands 27 extend across the end wall 12 of the boss 11 of the pad 10 and are secured substantially at their mid-length locations to the pad boss by the band 28, as described above. These mop strands are angularly arranged relative to each other to completely surround the plug 35 and the adjacent end portion of the inner tubular member 37 and have their ends disposed in surrounding relationship to the nut 48 and bound to this nut by a clamp band 50. The stitching 30 is also provided in the mop strands between the pad boss 11, and the band 50 to provide a substantially circular ring around the outer edge of the mop when the mop is in the operative position, as illustrated in Figures 6 and 7.

40 The pin 43 on the handle which extends through the straight slot 41 in the inner tubular member 37 also extends through the spiral slot 46 in the outer tubular member 45, and a pin 51, carried by the outer tubular member adjacent its end, remote from the pad 10, extends into the spiral slot 40 in the inner tubular member 37.

With this arrangement, when it is desired to wring the mop, the handle is first slightly rotated to move the pin 43 out of the lateral offset 42 at the upper end of the straight slot 41 and into the upper end of the inner slot, thereby releasing the handle for movement inwardly of the inner tubular member 37. With the end wall 12 of the pad 10 resting on the floor or in 55 a pail, the handle 15 is now manually forced downwardly and inwardly of the inner tubular member 37. As the pin 43 moves along the straight slot 41 and along the spiral slot 46 of the outer tubular member 45, it forces the outer tubular member to rotate through one complete rotation. As the outer tubular member 45 rotates one rotation, the pin 51 carried thereby moves around and along the spiral slot 40 in the outer portion of the inner tubular member 37, causing the outer tubular member to move longitudinally outwardly of the inner tubular member until the pin 51 reaches the outer end of the slot 40. This will move the screw-threaded end of the outer tubular member away from the boss 11 of the resilient pad a distance equal to the length of the spiral slot 40, and the rotation of the outer tubular member will simultaneously twist or wrap the mop strands about the portion of the inner tubular member 37 which re-

As the spiral slot 46 in the outer tubular member 45 has a length equal to the combined length of the spiral slot 40 and the straight slot 41 in the inner tubular member 47, when the pin 43 reaches the inner end of the straight slot 41, the outer tubular member will have moved outwardly of the inner tubular member a distance equal to the length of the straight slot, and the pin will also have moved along the outer tubular member a distance equal to the length of this slot, so that it will now be at the inner end of the spiral slot 46, and the spring 44 will be compressed substantially to the condition illustrated in Figure 9.

If the downward pressure on the mop handle 15 is now released, the handle will be forced outwardly of the inner tubular member 37 and the pin 42 will be moved from the inner to the outer end of the straight slot 41, returning the outer tubular member to the position in which its screw-threaded end is adjacent the boss 11 of the resilient pad, and the pin 43 is seated in the lateral offset 42 at the outer end of the straight slot 41.

The plug 35 is provided merely as an abutment for the inner end of compression spring 44, and may be omitted and a longer spring used, if desired, without in any way exceeding the scope of the invention.

The invention may be embodied in other specific forms without departing from the spirit or essential characteristics thereof. The present embodiments are, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A floor mop comprising a pad of elastic material including a central boss open at one end and having an end wall closing its other end and an annular web surrounding said boss at the open end of the latter and projecting outwardly therefrom, an elongated handle disposed substantially perpendicularly to said pad and coaxially of said boss, a tubular body receiving said handle and movable longitudinally and rotatably thereof, mop strands extending across the end wall of said boss and angularly related to completely surround said pad, means binding said strands intermediate their length to said boss, means binding said strands at their ends to said tubular body, and means surrounding said handle and engageable with said tubular body and rotationally and longitudinally movable relative thereto to move said tubular body away from said pad and stretchingly compress said mop strands, said pad being cupped within said strands when said strands are stretched.

2. A floor mop comprising a pad of resilient material including a central boss open at one end and having an end wall closing its other end and an annular web surrounding said boss at the open end of the latter and projecting outwardly therefrom, an elongated handle secured at one

end in said boss and extending substantially perpendicularly from said pad, a tubular body receiving said handle and disposed adjacent said pad, an externally screw-threaded nut secured on said handle at the end of said tubular body remote from said pad, mop strands extending across the end walls of said boss and angularly related to completely surround said pad, means binding said strands intermediate their length to said boss, means binding said strands at their ends to said tubular body, said tubular body having a screw-threaded counterbore in its end adjacent said nut, and a hand lever secured to said tubular body for moving the latter along said handle into engagement with said nut and then rotating said tubular body to thread the latter onto said nut and thereby stretch said mop strands and wrap the latter about the portion of said handle between said tubular body and said pad.

3. A floor mop comprising a pad of resilient material including a central boss open at one end and having an end wall closing its other end and an annular web surrounding said boss at the open end of the latter and projecting outwardly therefrom, an inner tubular member secured at one end in said boss and having a spiral slot therein extending longitudinally thereof from its other end and a straight slot 25 extending longitudinally thereof from the inner end of said spiral slot toward said pad, an elongated handle slidably received in said inner tubular member and having at its end adjacent said pad a pin slidably received in the straight slot in said inner tubular member, a compression spring disposed in said inner tubular member between said pad and said handle, an outer tubular member slidably and rotatably receiving said inner tubular member and having a 30 spiral slot extending longitudinally thereof a distance equal to the combined length of the spiral slot and the straight slot in said inner tubular member, said handle-carried pin extending through the straight slot in said inner tubular member and into the spiral slot in said outer tubular member, a pin on said outer tubular member adjacent the end thereof remote from said pad received in the spiral slot in said inner tubular member, mop strands extending across the 35 end wall of said boss and angularly related to completely surround said pad, means binding said mop strands intermediate their length to said boss, and means binding said mop strands at their ends to said outer tubular member at the end thereof adjacent said pad, said outer tubular member being movable away from said pad and rotatable relative to said inner tubular member upon movement of said handle inwardly of said inner tubular member against the force 40 of said spring.
